HAND SEAMER FOR CANS

Matthew M. Sedwick, Syracuse, N. Y., assignor to
 Continental Can Company, Inc., New York,
 N. Y., a corporation of New York

Application September 26, 1933, Serial No. 691,053

4 Claims. (Cl. 113—22)

The invention relates to new and useful improvements in hand seamers for cans wherein the cans may be clucked and manually rotated, and the seaming rolls manually moved at will 5 into contact with the metal parts for double seaming the end to the can body.

An object of the invention is to provide a hand seamer wherein the seaming rolls may be shifted at will into contact with the metal parts through 10 a manually operated cam actuated means.

In the drawings—

Figure 1 is a plan view of a hand seamer embodying the improvements;

Fig. 2 is a view partly in side elevation and 15 partly in vertical section of the same;

Fig. 3 is an enlarged view partly in side elevation and partly in vertical section, and

Fig. 4 is a detail showing one of the seaming rolls shifted into position for contact with 20 the metal parts.

The hand seamer includes a frame structure which may be clamped to a table or some other suitable support. Mounted for rotation in the frame is a shaft carrying a chuck. The shaft 25 is rotated manually. Also mounted in the frame is a can support on which the can is placed and then raised into contact with the chuck so that the can and end may be rotated for the seaming operation. There are first and second 30 seaming rolls mounted, respectively, at the outer end of arms which are pivoted for independent swinging movement on a supporting frame. Associated with both arms is a cam member provided with adjustable abutments which contact, 35 respectively, with the arms. Springs hold the arms in contact with these abutment members. The outer face of this cam actuated member is cam-shaped. A lever pivoted to the frame carries a roller which runs on the cam face of this 40 cam actuated member, and when this hand lever is moved in one direction, it will cam actuate and move one of the seaming rolls into engagement with the metal parts. When the hand lever is moved in the opposite direction it will cam actuate and move the other seaming roll into contact with the metal parts, and at the same time release the first seaming roll so that it is moved 45 out of engagement with said metal parts.

Referring more in detail to the drawings, the 50 hand seamer, as illustrated, includes a supporting frame having upright members 1, 1 spaced from each other. These upright members are preferably formed integral with a base member 2. Attached to this base member 2 are clamps 3, 3, 55 each of which is provided with a clamping screw

4. These clamps serve to firmly clamp the base member to a table or other support.

Joining the upper ends of the spaced frame members 1, 1 is a cap plate or bar 5. Mounted for rotation in a suitable bearing sleeve in said cap plate 5 is a shaft 6. This shaft 6 carries a bevel gear 7 which meshes with a bevel gear 8 mounted on a cross shaft 9 which is also journaled in the cap plate or bar 5. Attached to the outer end of the cross shaft is a crank 10. When this crank is rotated, it will impart rotations to the shaft 6. The gear 8 is of less diameter than the gear 7. Fixed to the shaft 6 is a chuck 11. Located directly beneath the chuck 11 is a can support 12. This can support 12 is provided with a 10 depending hub 13. The hub 13 is mounted for free rotation in a supporting member 14. Said supporting member 14 is recessed to receive the hub. At the lower end of the recess there is a flexible plate 15. A threaded hardened steel stud 15 is carried by the hub 13 and rests on this plate 15. The supporting member 14 is mounted for vertical movement in a sleeve 17 carried by a bracket base 18 which in turn is clamped to the supporting base member 2 by bolts 19, 19. 25

A lifting lever 20 is pivoted at 21 to the supporting member 14. This lever lies in a slot in the lower part of the supporting member 14 and extends out through an opening 22 in the wall of the sleeve 17. The lever 20 is formed with a cam 30 face 23 which terminates in a shoulder 24. The can to be seamed is placed on the supporting table 12, and then the lever 20 is lowered or moved downward, and this will operate through the cam face 23 to raise the support 14, and the can support 12 therewith. This will lift the can on which an end has been loosely placed into contact with the chuck and clamp the same firmly against the chuck. The plate 15 will yield to accommodate 35 any variations in the heights of the cans, and the shoulder 24 is so positioned that when the can end is in gripping contact with the chuck, then the shoulder moves on to the base plate and will hold the can support in its raised position. The operator after having lowered the lever, can 40 release the same, and by turning the crank 10, the can and can end will be rotated. 45

In order to roll the flange of the can end and the flange of the can body into a double seam, a first operation seaming roll 25 is provided. 50 This roll is pivoted at 26 to an arm 27 carried by a sleeve 28. The left-hand frame member 1 is preferably in the form of a flat bar. The upper end, however, is shaped so as to fit within a bearing sleeve 29 which rests on a shoulder 30 formed 55

in said member. The sleeve 28 is mounted on this bearing sleeve 29. Said bracket sleeve 29 has a projecting flange on which the sleeve 28 of the arm 27 rests.

5 The second operation seaming roll 31 is carried by an arm 32 which is formed integral with a sleeve 33. This sleeve 33 is also mounted on the bearing sleeve 29 and rests on the sleeve 28. The two arms 27 and 32 are thus mounted for independent swinging movement on the frame.

10 These arms are moved for bringing the seaming rolls into contact with the metal parts by a cam actuated member 34. This cam actuated member 34 is carried by a sleeve 35 which is also journaled on the bearing sleeve 29. The cap bar 5 is attached to the frame member directly above the bearing sleeve 29 and this sleeve 35 so as to prevent endwise movement of the parts mounted on this bracket sleeve 29. The cam actuated member 34 has a depending lug 36 carrying an abutment screw 37 which is threaded through said lug and bears against the outer face of the arm 27 carrying the seaming roll 25. A spring 38 is attached to the member 34 at one end and to the arm 27 at the other, and this spring will hold the arm in contact with this abutment screw 37. The cam actuated member 34 is also provided with a depending lug 39 carrying an abutment screw 40 which contacts with the arm 32 carrying the seaming roll 31. A spring 41 is attached at one end to this cam actuated member 34, and at its other end to the arm 32 and normally holds said arm in contact with the abutment screw.

15 The outer face of the cam actuated member 34 is shaped so as to provide an operating cam 42. On the outer end of this cap bar 5 is mounted a stud 43. Said stud is secured to the bar by means of a nut 44 which is threaded on to the shank of the stud. Mounted for free oscillation on this stud 43 is a hand lever 45. Said hand lever 45 carries a roller 46 which is adapted to cooperate with the operating cam 42 for actuating the member 34.

20 When the hand lever 45 is turned in a clockwise direction, the roller 46 will contact with the cam face 42 so as to forcibly turn the member 34 in a counter-clockwise direction. This will cause the abutment screw to force the arm 27 toward the can parts and bring the seaming roll into engagement with the flange of the can end, so that as the can is rotated by the operator through the crank 10, the metal parts will be rolled into a seam. This seaming roll is shaped so as to produce the first operation on the parts toward the forming of a double seam. After this seaming roll 25 has been held forcibly in contact with the metal parts for several rotations of the can, then the hand lever 45 is turned in a counter-clockwise direction, that is, the reverse direction. The roller 46 will turn the member 34 in a clockwise direction and then will release the arm 27 so that the roller 25 will move outward away from the seam. The roller running on the cam face will forcibly shift this member 34 so as to bring the seaming roll 31 into contact with the metal parts. Said roll is held in contact with the parts for one or more revolutions of the can, and this completes the formation of the double seam. After the seam is completed, the hand lever is brought back to a neutral position, which is the position shown in Fig. 1, and in this position, the cam actuated member 34 will be so set that both seaming rolls will be released from contact with the metal and the can may be removed and a new can placed for another seaming operation.

25 It will be noted from the drawings that the roller runs on a cam face formed by curving the same about a center which is radially a shorter distance from the cam face than the center about which the hand lever oscillates. When this roller is moved in either direction from the position shown in Fig. 1, it will cause the member 34 to swing on its pivot, and therefore, the rolls are forced into contact with the metal by a camming action, which enables great pressure to be brought to bear on the metal with little pressure applied by the operator to the lever 45 which manipulates the seaming rolls. When it is desired to make a tighter or a looser seam, then the abutment screws are adjusted and this will vary the ultimate pressure that may be exerted against the seam. This adjustment is also used to take care of different diameter cans. The cam face on the cam actuated member is so shaped that when the roller operating this member reaches a fixed position corresponding to the innermost position of the seaming roll, any further shifting of the hand lever will not affect the seaming roll, as the cam face from that point on and in that extreme position is concentric with the stud on which the hand lever is pivoted. This is clear from the position of the roller on the cam face, as shown in Fig. 4, where the operating roll is exerting its maximum pressure on the seaming roll through the cam actuated member.

30 It is obvious that minor changes in the details of construction and the arrangement of parts may be made without departing from the spirit of the invention as set forth in the appended claims.

35 Having thus described the invention, what I claim as new and desire to secure by Letters Patent, is—

40 1. A hand seamer including in combination, a frame, a chuck mounted in said frame for rotation about a vertical axis, a crank connected to said chuck for manually rotating the same, a rotatable can support associated with said chuck, a first operation seaming roll, an arm mounted for oscillation carrying said roll, a second operation seaming roll, an arm mounted for oscillation carrying said last-named roll, an operating member having a cam face, abutment members carried by said operating member and adapted to engage, respectively, said arms, springs for holding the arms in contact with the abutment members, a hand-operated lever and a roller carried thereby, said roller being adapted to engage the cam face of said cam-actuated member for forcibly operating the same for causing the seaming rolls 45 to contact with the metal parts.

50 2. A hand seamer including in combination, a frame, a chuck mounted in said frame for rotation about a vertical axis, a crank connected to said chuck for manually rotating the same, a rotatable can support associated with said chuck, a first operation seaming roll, an arm mounted for oscillation carrying said roll, a second operation seaming roll, an arm mounted for oscillation carrying said last-named roll, an operating member pivoted to said frame, adjustable abutment members carried by said operating member and adapted to engage, respectively, said arms, springs for holding the arms in contact with the abutment members, said operating member having a curved cam face at the outer side thereof, a hand-operated lever pivoted to said frame, a roller carried by said lever and engaging said cam face whereby when said lever is oscillated in one direction, one of said seaming rolls will be 55 60 65 70 75

forcibly caused to engage the can parts, and when oscillated in the other direction the other seaming roll will be caused to forcibly engage the can parts.

5 3. A hand seamer including in combination a frame comprising a base member, standards carried thereby and a cap bar secured to the upper ends of said standards and projecting beyond one standard, a rotatable chuck journaled in said 10 cap bar, a hand lever for turning said chuck, a can support adapted to cooperate with said chuck, means for raising and lowering said can support, a bearing sleeve mounted on one of said standards, arms mounted for independent oscillation on 15 said bearing sleeve, a seaming roll carried by each arm, a cam member mounted on said bearing sleeve and carrying adjustable abutment members adapted to engage, respectively said arms carrying the seaming rolls, springs for holding 20 the arms in contact with the abutment members, a pivot stud carried by said cap bar, a hand-operated lever pivoted on said stud, a roller carried by said lever and engaging said cam member, said cam member having a cam face so shaped 25 that when the lever is oscillated in one direction one of said seaming rolls will be forcibly moved into contact with the metal parts and when oscillated in the opposite direction the other seam-

ing roll will be moved into engagement with the metal parts.

4. A hand seamer including in combination a frame comprising a base member, standards carried thereby and a cap bar secured to the upper ends of said standards and projecting beyond one standard, a rotatable chuck journaled in said cap bar, a hand lever for turning said chuck, a can support adapted to cooperate with said chuck, means for raising and lowering said can support, 10 a bearing sleeve mounted on one of said standards, arms mounted for independent oscillation on said bearing sleeve, a seaming roll carried by each arm, a cam member mounted on said bearing sleeve and carrying adjustable abutment 15 members adapted to engage, respectively, said arms carrying the seaming rolls, springs for holding the arms in contact with the abutment members, a pivot stud carried by said cap bar, a hand-operated lever pivoted on said stud, a 20 roller carried by said lever and engaging said cam member, said cam member having a cam face so shaped that said roller when the lever is moved in one direction will force one of said seaming rolls to a predetermined set position, and 25 when said roller is moved in the opposite direction, it will force the other seaming roll to a predetermined set position.

MATTHEW M. SEDWICK.
